(57) **CLAIM**

The ornamental design for an interactive sound tablet, as shown and described.

DESCRIPTION

FIG. 1 is a front, top, right side perspective view of the interactive sound tablet, showing my new design;

FIG. 2 is a bottom, rear, left side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the interactive sound tablet and form no part of the claimed design.

The dot-dash broken line in FIG. 5 illustrates a boundary of the interactive sound tablet and forms no part of the claimed design.

1 Claim, 8 Drawing Sheets
